SYNCHRONIZING GENERATOR

Robert E. Kessler, Upper Montclair, N. J., assignor
to Allen B. Du Mont Laboratories, Inc., Passaic,
N. J., a corporation of Delaware

Application January 14, 1942, Serial No. 426,695

1 Claim. (Cl. 250—36)

This invention relates to a synchronizing generator that is particularly useful in television. By it, simplified circuits and very flexible switching are provided. The generator is very stable, even when operating at several widely different frequencies of line and field scanning. It can be made of light weight and small size so that it is readily portable, and, at the same time it is adjustable to a wide range of line and frame scanning standards. A cathode-ray tube of the built-in type is provided for monitoring, and both horizontal and vertical linearity test bars for the pattern are made available.

This invention relates to the production of sweep and blanking signals for iconoscopes, blanking pedestals for video amplifiers, and composite super-synchronizing signals. Sweep voltages are also supplied to auxiliary equipment, and test signals are supplied for checking sweep linearity.

In carrying out the invention a vacuum tube is caused to operate as a sine-wave oscillator at twice the desired line scanning frequency for an iconoscope. A second tube is caused to operate as a relaxation oscillator and is synchronized by the sine wave of the first tube so as to produce a pulse at the frequency of this sine wave, which frequency will be called the master frequency. This pulse of master frequency is used to synchronize another vacuum tube oscillator at half the frequency, thus producing a pulse at the desired line frequency.

The pulse at line frequency is used as a driving pulse for producing sawtooth wave forms as well as wave forms for super-synchronizing. The pulse at master frequency is also used to synchronize a chain of relaxation type oscillators for the purpose of dividing the master frequency down to the desired field scanning frequency. The pulse at field frequency is used to produce sawtooth sweep wave forms and also wave forms for super-synchronizing. Control tubes interlock the field frequency and power-line frequency to the master sine-wave oscillator to keep it at the proper frequency.

The time constants of the oscillator circuits can be quickly changed by switching arrangements so that the impedances of circuits are readily varied to provide the desired frequencies.

With this invention, pulses can be introduced into the super-synchronizing circuits so that the horizontal and vertical sweep wave forms can be readily tested for linearity, determining camera linearity and receiver linearity independently. A cathode-ray tube for observing the various wave

forms is built in the generator, with a switch which selects the signal or wave form to be observed as well as the proper sweep frequency time base for the respective signals.

5 The invention may be understood from the description in connection with the accompanying drawing, in which:

Fig. 1 shows a master pulse generator in which the frequency can be changed;

10 Fig. 2 shows a pulse generator from which a line frequency pulse suitable for television may be obtained;

15 Fig. 3 is a diagram indicating a chain of oscillators of the relaxation type to produce pulses at field frequencies and at line frequencies for a television system, and includes a block diagram showing how linearity test signals may be generated; and

20 Fig. 4 shows the pattern on a television receiver illustrating the linearity test.

In the drawing, reference character 1 indicates a wire leading from a sine-wave generator to the transformer 2 of the relaxation oscillator 24 to synchronize the oscillator 25. One end of the 25 primary 3 is connected through load resistor 4 to ground and the other end is connected through condenser 5 to grid 6 of the oscillator tube 7. Provision is made by means of switch 8 for connecting grid 6 to ground through any one of a series of resistors 9 which will cause the tube to 30 oscillate at a number of desired frequencies that may be selected by means of the switch. The small variable resistor 10 is to adjust the frequency more closely when necessary. The positive side of a source of voltage is connected through 35 the secondary 12 of the transformer 2 to the plate 13 in the known way, and the master pulse at the selected frequency is taken off by the lead 14 between the cathode 15 and resistor 16 which is 40 grounded.

A signal at the desired frequency applied by the lead 1 causes the tube 7 to oscillate in synchronism with it, thus producing a positive pulse. When the input signal at 1 is a sine wave at master frequency the output signals at 14 and 14' are 45 positive pulses occurring at the master frequency when the proper resistor 9 is used.

In order to obtain a pulse at one-half the 50 master frequency, which is the line scanning frequency, the master pulse on 14 is applied to another relaxation oscillator 25 such as shown in Fig. 2. The pulse is applied to the primary 15' of the transformer 16'. The time constants for this oscillator, which depend upon the condenser 17 and the resistors 18 in series with the small ad-

justable resistor 19, are selected so that the frequency of this oscillator 20 is exactly half of the first one when the master pulse from the first oscillator is applied to it.

In the diagram shown in Fig. 3 a master sine-wave oscillator 23 is shown as one which may generate a 31.5 kc. sine wave, for example. A master oscillator control tube 21 is connected to it, which is in turn controlled by direct current from a lock-in circuit 22 connected to the field frequency pulse of 60 cycles. The signal from the 31.5 kc. oscillator 23 which is at twice line frequency is applied to the master pulse oscillator 24, which is the oscillator shown in detail in Fig. 1. The signal from the master pulse oscillator 24 is applied to the oscillator 25, which is shown in detail in Fig. 2, where the frequency is halved, and is the present standard 15,750 cycles per second, or 525 lines per frame for television line scanning.

The frequency of the signal from the master pulse oscillator 24 is divided 7, 5, 5 and 3 as indicated at 30, 31, 32 and 33 to provide a pulse at the field frequency of 60 C. P. S., or frame frequency of 30 C. P. S. with interlaced scanning. It will be understood that the resistances such as resistances 9 (Fig. 1) will be inserted in accordance with the frequency of the input signal at 1. At the same time the resistances 18 (Fig. 2) and all the other corresponding resistances in the oscillators indicated in Fig. 3 at 23, 24, 25, 30, 31, 32 and 33, will be correspondingly changed. These blocks indicate oscillators similar to those shown in Figs. 1 and 2. For changing the resistances in these oscillators, switches 8 and 8' and corresponding switches at the other oscillators indicated in Fig. 3 are connected together or ganged as indicated by the dotted line L (Figs. 1 and 2) so that they will be moved correspondingly and simultaneously, thus providing the needed time constants for the respective oscillators at all times.

In a similar way, pulses at other frequencies such as 441 lines at 30 frames per second or 625 lines at 15 frames per second, for example, can be obtained. The following table shows suitable data for practical cases:

Line	Frame	Master freq.	Line freq.	1st divider	2nd divider	3rd divider	Field freq.
441	30	C. P. S.	C. P. S.	C. P. S.	C. P. S.	C. P. S.	
		26,460	13,230	3,780	540	180	60
525	30	31,500	15,750	4,500	900	180	60
625	15	18,750	9,375	3,750	750	150	30

Since the relaxation oscillator 24 (Fig. 1) described herein is very stable, the switching arrangements shown in Figs. 1 and 2 can be safely utilized for quickly changing to different scanning frequencies over a wide range. For example, the resistors 9, shown connected in by the switch 8, may be of such size that the master pulse frequency on leads 14 and 14' is 31.5 kc. By changing the switch 8 to connect other resistors 9, the frequency can be quickly changed to values predetermined by the size of the resistors.

In Fig. 3, lead 40 connects from oscillator 25 to a carrier generator 41 and to a horizontal super-synchronizing shaping device 42. A lead 43 connects the generator 41 to a keying tube 44. A lead 45 also connects from oscillator 33 to keying tube 44. A lead 46 connects keying tube 44 to the mixer 47 so that the frequencies of the oscillators 31 and 33 are applied to this mixer 47. Switch 48 and resistance 49 are for partly

short-circuiting the keying tube 44, thus allowing the signal from generator 41 to appear at the mixer 47 continuously in a weak form and to be keyed to full strength by the signals from oscillator 33.

The mixer 47 is also adapted to another type of signal so that when the switch 52 is closed a signal is introduced from the divider stage 31 of Fig. 3. By closing the switch 48 a small amount of carrier frequency generated in 41 is introduced into the composite super synchronizing signal which is delivered from 53 to the remaining television equipment. In practice this approximately 500 kilocycle signal which in the instance of the specific frequencies illustrated in Fig. 3 would be 535.5 kilocycles, is keyed into the composite synchronizing signal for a short interval at field frequency periodicity by pulses from the divider stage 33 of Fig. 3. The box 41 consists of two multiplier stages which increase the line frequency pulses from box 25 to an exact harmonic which in the case illustrated is the 34th harmonic. Then, by introducing a small amount of this 34th harmonic signal which is at a frequency of 535.5 kc. (15.75 kc. $\times$ 34) into the mixer 47 and then into the composite super-synchronizing illustrated at box 53, and applying the same to a television receiver the pattern will be such that each line will have a modulation of 34 bright and dark bars. The number of bars of course vary according to the particular scanning combination that is chosen. The closing of switch 48 therefore causes uniform interval markings to appear as vertical lines and consequently a television receiver tube will have a calibration of its linearity in the horizontal direction.

When the switch 52 is closed impulses from the divider stage 31 of Fig. 3 are introduced into the television receiver as indicated by the groups 59 of lines as shown in Fig. 4. The lead 54 comes from the connection in box 31 which corresponds to the connection between transformer winding 15' and condenser 17 of Fig. 2 except that the connection is the corresponding one in the divider tube in box 31. By choosing this pickoff point the wire 54 will contain signals for example of 900 C. P. S. of large intensity generated directly by the relaxation oscillator of the divider stage 31 and also there will be present the weaker signals which are fed to that point for synchronizing purposes from the earlier divider stage 30 having a frequency of 900 C. P. S. The strong signals will occur at 900 C. P. S. or once for every 35th oscillation ($\frac{1}{7}$ of $\frac{1}{3}$ of 31.5 kc. in the case illustrated) of the master pulse oscillator 24. The weaker pulses which are fed through from the box 30 to synchronize the oscillator of 31 will occur five times as often, or at $\frac{1}{7}$ of 31.5 kc., or 4500 C. P. S. Thus there are strong equally spaced impulses 66 between which four weaker impulses 65 occur. In Fig. 3 the master pulse oscillator 24 is assumed to be running at 31.5 kilocycles.

A first divider stage 30 divides this frequency by a factor of 7 and the second divider stage 31 divides further by a factor of 5. Since the divider 25 which delivers the line frequency pulses operates at half the frequency of the master oscillator 24, the master oscillator 24 applies impulses at every half line of scanning. Therefore the 4500 C. P. S. impulses which are fed to wire 54 by the synchronizing action of box 30 places impulses every 7th half line of scanning, since the line scanning frequency $15,750 \div 4500 = \frac{1}{2}$ of 7,

and the stronger 900 C. P. S. impulses supplied by divider 31 to wire 54 put an indicator mark on every 35th half line since $15,750 \div 900 = \frac{1}{2}$ of 35. The result of this signal when switch 52 is closed gives an appearance on the receiving tube screen as shown in Fig. 4. There will be a series of calibration markings down the center of the television picture and another series of calibration markings at the ends of the lines or at the edges of the picture since the markings at the ends of the lines are supplied because of the rapid return time.

In Fig. 4 reference character 56 represents the horizontal dimension of a received television picture which is four units wide in comparison with the vertical dimension 57 which is three units high. For the linearity tests the receiving tube may either have a picture upon which the linearity test calibrations are superposed, or the transmitter may be sending an artificial white field upon which the linearity test calibrations appear visibly.

Closing of the switch 48 (Fig. 3) introduces on the pattern of Fig. 4 the 34th harmonic 535.5 kc., for example, of the line frequency 15.75 kc. This results in the dark vertical stripes 59 separated by the light vertical stripes 60. Approximately 30 of these dark vertical stripes 59 would be visible across the pattern since the remaining 4 occur on the return trace which is blanked out. Since these vertical bars occur uniformly in time, they would appear uniformly spaced on the receiving screen only when the horizontal linearity is correct. Thus the receiver scanning may be checked for linearity and may be adjusted by use of these bars or stripes 59.

When the picture test pattern is placed on the transmitting camera its linearity can be checked independently by comparing the line markings of the test pattern with these uniform time interval markings 59 as seen on the receiving tube screen, Fig. 4. Furthermore, if the receiver should be non-linear it is still possible to adjust accurately the transmitting camera linearity independently and thus avoid the difficulty which has been encountered in the past whereby a pattern might be reproduced on the receiver with apparent linearity which in fact

was a combination of a non-linear error at the transmitter camera and a corresponding corrective non-linearity at the receiver. By this method of testing linearity it is possible to adjust the absolute linearity of the transmitter camera independently of the adjustment of linearity of the receiver scanning.

In Fig. 4 reference character 62 indicates a linearity calibration down the center of the picture which will be introduced by the closing of switch 52 of Fig. 3. This calibration appears as a series of fine lines 65 every fifth one of which is introduced as shown at 66 as a heavy line due to the dividing action of 5:1 between boxes 30 and 31 of Fig. 3, in the particular example illustrating this invention. In any combination of line and field scanning there will be at the box 31 of Fig. 3 a signal available to give evenly spaced indicating calibrations. Time can therefore be used for checking vertical linearity and if the vertical scanning, for example, tends to be slower at the top than in the middle these calibration marks would appear to be packed at the top. In practice the switches 48 and 52 enable these linearity test signals to be inserted at will. In addition to the calibration strip 62 down the center of the picture there will be calibration indications 67 and 67' caused by the alternate signals provided from divider stage 31. This indicating strip is actually spread into two parts because of the rapid return of the spot at the receiver horizontal scanning. In this way both horizontal and vertical linearity indications will be given over all the useful regions of the picture area.

What is claimed is:

In a device of the character described, an oscillator for generating a predetermined frequency, means to control said frequency, a series of frequency dividers connected to said oscillator, and means to obtain a composite signal from said oscillator and one of said frequency dividers in which a mixer is provided for said composite signal, a keying tube is provided between said oscillator and said mixer, and a switch and by-pass resistance is provided across said keying tube.
